MOLDING FOR CABINETS OR THE LIKE

John R. Morgan, Wheeling, Ill., assignor to Amerock Corporation, Rockford, Ill., a corporation of Connecticut

Filed Nov. 23, 1966, Ser. No. 4,780

Term of patent 14 years

(Cl. D13—6)

FIG. 1 is a front elevation of a section of molding embodying my new design.

FIG. 2 is a sectional view taken along the line 2—2 in FIG. 1.

FIG. 3 is a sectional view taken along the line 3—3 in FIG. 1.

FIG. 4 is a bottom view of the molding.

FIG. 5 is a fragmentary perspective view of the molding.

The molding is of indeterminate length and has throughout its length the shape and configuration typified by the section of the molding shown in the drawing.

I claim:

The ornamental design for a molding for cabinets or the like, as shown and described.
